COMBINED CLEANER AND DRIER FOR FLOORS OR THE LIKE

Howard A. Anderson, Pittsburgh, Pa., assignor to Bissell
Inc., Grand Rapids, Mich., a corporation of Michigan

Filed Mar. 31, 1960, Ser. No. 60,049

Term of patent 14 years

(Cl. D9—2)

FIG. 1 is a side elevation of a combined cleaner and drier for floors or the like, showing my new design, the side not shown being substantially the same except for the cord support prongs on the handle; and

FIG. 2 is a front elevational view thereof, the back view being substantially the same except for the electric switch and cord outlet which are shown beneath the handle in FIG. 1.

The dominant features of my design reside in the portions shown in full lines.

I claim:

The ornamental design for a combined cleaner and drier for floors or the like, substantially as shown and described.
